UNITED STATES PATENT OFFICE.

ALFRED M. MEYERS, OF MERRIAM, KANSAS.

PLATE-BENDING MACHINE.

1,345,386.

Specification of Letters Patent.

Patented July 6, 1920.

Application filed April 6, 1918. Serial No. 226,992.

To all whom it may concern:

Be it known that I, ALFRED M. MEYERS, a citizen of the United States, residing at Merriam, in the county of Johnson and State of Kansas, have invented certain new and useful Improvements in Plate-Bending Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to plate bending, and more particularly to a machine for bending heavy metal plates of the type used in large retorts, tanks, etc., the principal object of the invention being to bend the plates while cold.

In accomplishing this object I have provided improved details of structure, the preferred forms of which are illustrated in the accompanying drawings, wherein:—

Figure I is a perspective view of a plate bending machine constructed in accordance with my invention, the figure illustrating a machine comprising four air hoists, although the number or character of the lifting devices is immaterial, provided they are sufficient for the purpose.

Fig. II is a front view of the machine, with the pull chains removed for better illustration this figure showing but three air hoists and indicating a machine shorter in length than that shown in Fig. I.

Fig. III is a vertical cross section of the machine, as on the line indicated by III, Fig. I; illustrating use of auxiliary shaping ribs.

Fig. IV is an enlarged vertical cross section of members of the frame, illustrating the anchor socket for the metal plate, and the cam for holding the inner edge of the plate.

Fig. V is a detail view of the fixed bending rib, illustrating mounting of an auxiliary rib of sharper curvature.

Fig. VI is a detail view of a modified form of fastening of hoist chains to the metal plate to be bent.

Referring more in detail to the drawings:—

1 designates a platform comprising longitudinal, foundation beams 2 and platform beams 3, the latter preferably composed of

double channel irons arranged back to back to afford substantial support for and connection with the upper frame and shaping members presently described. There may be any suitable number of platform beams, but preferably one for each bending rib, as said ribs are extended between the channel pairs and bolted thereto to firmly mount the ribs in the machine. The platform also comprises an intermediate, longitudinal I beam 5 which is cut away at its upper edge, as at 6, to seat the platform beams 3. At the rear of the machine are standards 7, preferably of angle irons, which seat on the rear ends of the beams 3, and have brace plates 8 bolted thereto and extended between the angle members and permanently attached to said members to firmly support the standards. Each of said standards carries at its upper end a forwardly extending plate 9, for connection with a frame beam 10, all of which latter are seated on the platform beams 3, and extend upwardly therefrom at an angle of more than 90 degrees in order to provide the necessary bending space at the front of the machine. Each of the frame beams 10 is also preferably composed of channel irons, arranged in pairs with the members of each pair lying along opposite sides of the standard plate 9 and bolted thereto to stabilize the beam.

12 designates permanent bending ribs, each of which comprises a body member, having a rearwardly directed neck 13 located between the channel members of the frame beam 10, and extended downwardly between the members of the platform beam 3 and connected to the I beam 5 by an axle neck 13' that lies along the rear face of the I beam 5. The said neck is bolted to the frame beam, the platform beam and I beam to hold it securely and rigidly in place, as it is against this bending rib that the pressure is exerted during operation of the machine. I prefer to locate angle irons 14 at the front of the I beam through which the bolts that attach the flanges 13 to the necks of the bending ribs may be secured.

The upper corners of the bending ribs 12 are braced by angle irons 15, which are bolted to the said ribs and to the standard plates 9. All of the permanent bending ribs in the machine are connected by a cross channel 16, which lies against the upper ends of the ribs and is bolted to the flanges of the several angle irons 15. The angles 15 are

paired on opposite sides of the respective bending ribs and of the standard plates 9, so that the connecting bolts extend through the bending ribs and flanges of both paired members 15.

The forward edges 17 of the several permanent bending ribs 12 preferably have like and definite curvature, for bending a plate to that particular curvature, but should it be desired to bend a plate to a different curvature, auxiliary ribs of such different curvature may be temporarily attached to the permanent ribs 12, as will presently be more fully described.

15 The front or curved edge of each of the ribs 12 extends to the front edge of the frame beam 10 and is spaced from the top of the platform beam 3, so that a pocket is formed beneath the bending rib for receiving the rear edge of the metal plate or sheet which it is desired to shape or bend. As the shaping or bending of the metal plate is effected by drawing the same from its forward edge against the ribs 12, it is necessary to firmly hold the rear edge of the metal plate to be shaped and brace the bending ribs. This is effected by extending transverse stops 18 between adjacent bending ribs, near their rear ends. These stops 20 preferably comprise forwardly facing channel irons which are attached to the bending ribs by angle irons 19-19' one flange of each of which is attached to the web of the channel iron and the other flange securely bolted to the adjacent bending rib, it being apparent that the irons 19-19' may register on opposite sides of the bending ribs and the same bolts used for both angles. With this arrangement the metal plate to be 25 shaped may be drawn against the curved edges of the bending ribs and against the lower flanges of the channel irons, so that the plate is bent at the channel position to start the curvature along the lines of the bending rib.

To draw the metal plate and effect the bending thereof, I utilize compressed air by means of hoists 21 which are adjustably supported from the top of the frame. Support of the hoists is preferably effected by providing the upper end of each hoist with a link 22 that extends in the channel formed by the members of brackets 23 on the upper end of the frame beam 10, and is carried by the cross pin 24, so that the link and hoist may swing freely on a pivotal mounting.

Also fixed to the upper end of each of the frame beams 10, is a hanger arm 25, preferably composed of paired channel irons, the members of which extend on opposite sides of the bracket 23 and frame beam 10 and are secured thereto by bolts 26 to connect the arm members and attach the same 60 to the frame.

Located between the members of each of said arms 25 at the front end thereof, is a pulley 27, over which is run a cable 28, the lower end of which is attached to a band 29 on the lower end of one of the air hoists 21. 70 The rear end of the cable 28 extends between the members of plate 23 and channel beam 10, and runs over a pulley 30 mounted between the members of arm 25, as is the pulley 27. The rear end of the cable carries 75 a weight 31 which is adapted for counter balancing the hoist 21, so that the hoist may easily assume any desired position and conform to the bending operations.

The upper end of the frame is preferably 80 braced to retain all of the parts in functional relation, by a channel 33 attached to the rear flanges of the several beams 10, and a channel 34 which is attached to the upper ends of said beams 10 by angle pieces 35 85 that are bolted to the bases of both beams.

Each hoist 21 comprises a piston (not shown), having a rod 36 provided at its free end with a hook 37 which is connected with the upper link of a chain 38, the inner 90 link of which has a hook 39 which may be attached to the top of the I beam 5, the chain being of sufficient length to extend around the outer edge of the metal plate 40 that is supported on the platform beams 3 in position to be bent.

Each of the hoists is fed through a flexible hose 42 having an individual valve 43 and connected with a supply manifold 44, that may be connected with any suitable 100 source of supply (not shown) and provided with a general control valve 45.

In order to hold the inner edge of the metal plate and prevent its slipping when the outer edge is drawn upwardly to bend 105 the plate, I provide a clamp at the pocket portions, preferably comprising cams 46, which are fixed in a shaft 47 that is journaled in bearing 48 on the I beam 5. The shaft 47 extends beyond the ends of the 110 body of the machine and is operated by hand levers 48', one of which is attached to each end of the shaft 47 and is movable along a quadrant 49. Each lever 48' has a pawl 50 co-operative with the quadrant and 115 provided with a hand latch 51, so that the shaft and the cams carried thereby may be retained in any set position.

When the machine is idle, the shaft rests with the cams lowered (Fig. III), so that 120 the edges of a plate to be bent may be projected into the pocket at the base of the bending rib. When the plate is placed on the platform the shaft is rocked to force the cams against the under surface of the inner 125 edge of the plate and press the plate against the lower edge of the stops 18 (Fig. IV). In this way the inner edge of the plate is clamped to prevent its displacement when bent around the ribs 17.

As above stated, the permanent bending ribs 12 being of fixed curvature or radius, auxiliary plates must be used. Such use is effected by attaching auxiliary plates 50' to the permanent plates 12, preferably by bolts 51', the auxiliary plates abutting against the channel irons so that their curved edges are practically continuous with the curved edges of the permanent ribs at the inner ends of the latter. It is apparent that there is a slight difference of curvature at that point but this is not sufficient to affect the use of the machine.

In using the machine, assuming the parts to be constructed and assembled as described, and it is desired to bend a plate to the curvature of the permanent bending ribs 12, the metal plate 40 is located on the platform beams 3 with its inner edge located in the pockets heretofore described, and preferably abutting against the frame beams 10, and the inner edge of the plate clamped by the cam mechanism heretofore described. The chains 38, which are usually left connected with the I beams, are then run around the outer edge of the plate 40 and connected with the hooks on the extended hoist rods 36 (see Figs. I and III).

With the parts so arranged, compressed air is admitted to the outer ends of the active hoists 21 to force the pistons upwardly, thereby drawing the rods 36 and chains 38. This drawing of the hoist rods and chains lifts the free edge of the metal plate and, as the inner edge of the plate is anchored in its pocket in the machine, the plate is drawn over the curved edge of the bending ribs 12 and assumes its curvature.

It will be noted that the bending rib 12 is only of sufficient length to engage about one-half of the metal plate, so that only one-half of the metal plate is bent at a single operation. After the first half of the plate is bent, it is reversed and the bending completed, so that after the second operation the curvature is over the entire width.

I provide for reaction of the metal by using bending ribs of less radius than that required for the metal plate, so that when the latter is released after being bent over the bending ribs it will react to the proper curvature.

Should it be desired to bend a metal plate on a radius other than that provided for by the permanent bending ribs 12, auxiliary ribs 50' of the proper radius and curvature are attached to the permanent ribs 12, and the operation just described is performed.

In the modified form shown in Fig. VI, the hoist chain is shown anchored to an angle iron—that is, removably attached to the outer edge of the metal plate 40, preferably by bolts, so that the iron may be easily applied to and removed from the plate without damage thereto.

Should it be desired to bend a plate on a wave or taper line, ribs of different radii may be arranged in the machine and the metal plate drawn thereagainst, different portions of the plate taking their shape 70 from the particular ribs against which they are drawn.

It is apparent that any suitable number of hoists may be used for lifting the metal plates and that plates of any length within 75 the limits of the machine may be bent by proper arrangement relative to the air hoists.

It is further apparent that while I have in the description, referred to specific details of construction, this has been principally for explanation and without intention to limit the scope of the invention.

Having thus described my invention, what I claim as new therein and desire to secure 85 by Letters-Patent, is:—

1. In a plate bending machine, a platform, a base,—a beam on the said base, a plate clamping member in rear of and beneath the beam to clamp a plate against the 90 same, the clamping member comprising a rotatable shaft and a cam on said shaft, a plate bending flexible member anchored at one end of the base and a power device at the other end of said flexible member. 95

2. In a metal bending machine, fixed shaping means, means for supporting a plate to be bent, a hoist pivotally mounted at one end, a cable connected at the opposite end of the hoist and provided with a counterbalance, and means connected with the hoist for drawing the plate against the shaping means. 100

3. In a metal bending machine, a base, a horizontal beam extending lengthwise of the 105 base, a plurality of curved templet plates carried by the beam and curved outwardly and upwardly therefrom, a shaft extending longitudinally of the base and beneath the beam, cams fixed to said shaft to simultaneously move into plate-clamping position so as to clamp plates between the cams and the templet-carrying beam, a power device above the templets, and a flexible connection anchored to the base and engageable with 115 the free ends of plates secured between the cams and beam whereby when power is applied to the power device, the free ends of the plates will be bent upwardly against the curved portion of the templets. 110

4. In a metal bending machine, a base, a shaping templet comprising a plate having curved outer ends projecting upwardly from said base, means for supporting one end of a plate to be bent, the other end of the plate 125 being free, a pivoted hoist positioned above the templet, a flexible connection anchored to the base and engageable with the free ends of the supported plate, said flexible connection being connected to the hoist 130

whereby movement of the hoist in one direction will bend the free end of the plate against the curved surface of the templet, and a counter-balance weight connected to the end of the hoist distant from its pivotal connection.

5. A plate bending machine comprising in combination, a base, a plurality of form members on said base, means on said form members for varying the curvature thereof, means opposite said form members and spaced therefrom to receive the edge of the plate to be bent, flexible members each secured at one end to said base and disposed around the free edge of the plate to be bent, and power means to operate the flexible means to draw the plate against said form members.
- 10
- 15

6. A plate bending machine comprising a frame, means adapted to receive and hold 20 one edge of a plate to be warped, said means including complementary form and stop members disposed on opposite sides of the plate, a chain adapted and arranged for application to the opposite side of the plate 25 from the form member, one end of the chain being adjacent to the fixed edge of the plate and the body of the chain being disposed around the remote free edge of the plate, and power means to operate the chain to draw 30 the plate tightly against said form member, said power means being connected to a part of the chain remote from the said end which is anchored.

In testimony whereof I affix my signature. 35
ALFRED M. MEYERS.
